UPRIGHT CONVENIENCE PANEL FOR HOSPITAL ROOM

William C. Boteler, Mission, Kans., assignor to Puritan
Compressed Gas Corporation, Kansas City, Mo., a cor-
poration of Missouri

Filed Feb. 25, 1963, Ser. No. 73,695

Term of patent 14 years

(Cl. D83—1)

Fig.1.

Fig.2.

Fig.3.

FIG. 1 is a perspective view of an upright convenience panel for hospital room, showing my new design;

FIG. 2 is a side elevational view of the left side of the upright convenience panel for hospital room illustrated in FIG. 1, the right-hand side of the upright convenience panel for hospital room also being plain and unornamental; and

FIG. 3 is a plan view of the upright convenience panel for hospital room shown in FIG. 1.

I claim:

The ornamental design for an upright convenience panel for hospital room, substantially as shown and described.
